CLAIM

The ornamental design for a display screen or portion thereof with graphical user interface, as shown and described.

DESCRIPTION

FIG. 1 is a front view of a display screen of portion thereof with graphical user interface, showing the new design; FIG. 2 is a front view of a second embodiment thereof; and, FIG. 3 is another front view of the graphical user interface of FIG. 1, showing alternative broken line subject matter. The outermost broken line illustrates an electronic device, the broken line at the periphery of the graphical user interface illustrates the display screen, and the closely spaced broken line showing of text, numbers and icon elements illustrate portions of the graphical user interface. None of the broken lines form part of the claimed design.
